UNITED STATES PATENT OFFICE.

JAMES L. MCQUARRIE, OF BOSTON, MASSACHUSETTS, ASSIGNOR TO THE NEW ENGLAND TELEPHONE AND TELEGRAPH COMPANY, OF SAME PLACE.

TELEPHONE CIRCUIT AND APPARATUS.

SPECIFICATION forming part of Letters Patent No. 443,145, dated December 23, 1890.

Application filed June 27, 1890. Serial No. 356,949. (No model.)

To all whom it may concern:

Be it known that I, JAMES L. MCQUARRIE, residing at Boston, in the county of Suffolk and State of Massachusetts, have invented 5 certain Improvements in Telephone Circuits and Apparatus, of which the following is a specification.

To obtain inductive neutrality in telephone-circuits it has for some time been customary 10 to construct such circuits as otherwise would be exposed to inductive disturbances upon the plan patented to David Brooks February 22, 1881, No. 238,195, in which, instead of being completed through the earth, the several 15 exposed circuits are provided with a closely-adjacent and substantially parallel metallic return-wire, whereby the induced currents developed on either side of the circuit from the source of disturbance are neutralized by the 20 equal but opposite currents developed by the same source on the other side of the circuit.

It is not new on economical considerations to form combinations of a plurality of lines which are ordinarily single wire or earth re- 25 turn-circuits, each supplying its own sub-sta-
tion in such a way that said stations of either one of a pair of such circuits may, in combi-
nation with its own line, use the line of the remaining circuit of said pair, and so form of 30 the two, as occasion may require, a temporary metallic circuit. Nor is it new, also, on the score of economy to connect a plurality of sub-stations with a regularly-constituted metallic circuit in such a way that each sub-sta-
tion while using the circuit for conversational 35 purposes shall have a clear and balanced metallic circuit unencumbered by interposed electro-magnets.

This invention relates to these general 40 classes of telephone-circuits.

In all metallic circuit systems with which I am familiar there are certain practical draw-backs, which by my invention I aim to avoid or overcome, and, generally stated, its object 45 is to provide a metallic telephone-circuit which may be common to a plurality of sub-stations, in which each sub-station has at all times the use of a metallic circuit with all the advantages inherent therein, in which each sub-sta-

tion may be called from the central station 50 without giving the alarm at the other station, and may also signal the central station without signaling the other station, the calls from both sub-stations being received upon the same call-receiving instrument at the central 55 station, and in which but one spring-jack or other switching device or annunciator per double-wire circuit is required.

In pursuance of this object my invention comprises, in a telephone-exchange, a metallic circuit extending from a central station to two sub-stations, call sending and receiving apparatus at both central and sub stations, means consisting of special circuit arrangements at the sub-stations and special switch- 60 ing appliances associated with the call-generator at the central station, whereby the central station may signal either sub-station independently and individually without alarming the other, and appliances at each sub- 65 station whereby calls are enabled to be sent from either to the central station without affecting, also, the call apparatus at the other sub-station. 70

More specifically, the essence of my inven- 75 tion consists in placing the call apparatus of the most distant sub-station in the actual normal metallic main-line circuit, including the call apparatus of the sub-station nearest to the central station in a separate branch 80 diverging at the said sub-station from one of the main-circuit wires and extending therefrom after passing through the said intermediate-station call apparatus, to earth at the most distant sub-station, and in providing a 85 switching device at the central station whereby the call-generator there may at will be included in the metallic circuit of the main line to ring the most distant station-bell, and alter- 90 nately may be included in an earth-com-
pleted circuit to ring the bell of the nearer station.

It consists, also, in combining with the two wires of the main-line metallic circuit and with a single spring-jack switch and annun- 95 ciator at the central station a circuit-chang-
ing device at the intermediate station, where-
by when it is desired to send a call to the

central station the said call apparatus may be transferred from the earth-branch extension to the metallic circuit, and at the same time the main line leading to the station beyond is disconnected, so that the call-signals are sent in the direction of the central station only.

It consists, also, in combining with the said instrumentalities automatic and manual circuit-breakers in the earth branch extension at the most distant station to provide against the contingency of an accidental earth fault at some point on the main circuit, and the possible confusion in sending and receiving call-signals resulting therefrom, and to aid, also, in perfecting the electrical balance of the talking-circuit.

It consists, also, in the special connections and circuit arrangements whereby the telephones at the sub-stations may be combined with the foregoing devices in such a way that they shall be on open circuit when not in use and connected when in use with both of the metallic-circuit wires.

The drawing which accompanies and forms a part of this specification is a diagram clearly indicating the features and scope of my invention. It shows a double wire or metallic circuit L, extending from a central station C to a terminal sub-station B, and passing through and serving also an intermediate sub-station A. At the central station, as is well understood, a number of such circuits center, these being indicated by the presence in the diagram of the detached portion of an independent sub-station circuit L². Each circuit is furnished with a single spring-jack or other like connecting device b and a call-receiving annunciator a. A key-board K may be provided with a number of pairs of connecting-cords c, each comprising two flexible conductors c' and c², and for each pair of connecting-cords a pair of circuit-changers k, which when depressed act to send outgoing call-signals, while when remaining unpressed they allow each of the two flexible conductors of one of the connecting-cords to electrically join directly one of the conductors of the other connecting-cords, and by means of these double cords the two wires of any metallic telephone-circuit may be connected with the two wires of any other metallic telephone-circuit. For this purpose the outer end of each core of a pair is furnished with a plug-connector arranged with two conducting parts forming, respectively, terminals of the two inclosed conductors of each cord. The two conductors c' unite with the central conducting stem of their respective plugs, and these terminate in the rounded tip p' of the plug, and the two conductors c², passing through their respective cords, are attached at their respective plugs to the metallic sleeve or outer portion p² of the plug-stem. The tip p' and sleeve p² are of course insulated from each other, and the insulation is indicated by the ring r, which appears in the unconnected plug

immediately behind the convex tip. When the plugs are inserted in the spring-jacks, the tip breaks the original contact thereof and makes contact itself with the spring portion thereof, while the sleeve portion of the said plug in turn makes contact with the frame portion of the said jack, it being understood that the said spring and frame of the said spring-jack are or may be for the purposes of this case regarded as being respectively the terminals of the metallic main circuit represented by the said spring-jack.

In the key-board K the ends of the two flexible conductors c', each extending from the tips of their respective plugs, are attached to contact-springs d', while the other conductor c² of each cord of the pair is in like manner attached to a similar contact-spring d². The springs d' and d² of each cord are controlled by one of the circuit-changers k. When the circuit-changers are undepressed, the said springs of both cords rest on front contact-points. The contact-points on which rest the springs d' are united by the wire 12, and the points forming the resting-contacts of the springs d² are united through the wire 13, and it will now be seen that when the two plugs of a pair of connecting-cords are inserted in the spring-jacks of a pair of metallic circuits the path of the connecting-link through the key-board is from the tip p' of one through the conductor c' thereof, spring d', wire 12, spring d², and conductor c² of the other to the tip of the remaining plug, and that the two sleeve portions of the two plugs are united through the two sections of conductor c², the two springs d² and the wire 13 uniting the said springs. The operator's telephones T and t are included in a bridge from the wire 12 to the wire 13, and when so placed do not interfere with through communication, while both lines can, if desired, be readily communicated with. The said telephones will of course in practice be common to a number of connecting-loops, and will be provided with suitable switches to disconnect them from any special pair when two subscribers' lines are connected. The contact-springs d' and d², controlled by the circuit-changers k, have reverse contact-points, against which they are caused to impinge when the circuit-changers are depressed. Those which are marked e and e' are respectively the back contacts for the terminal springs d² of the sleeve-conductors, and are united together by a wire 14 and both by wire 15 to a contact-button v² of a hand-switch S, which in practice is, for the convenience of the operator, placed on the table E, and those which are designated g and g' are the back contacts for the terminal springs d' of the tip-conductors. They are united by a wire 16, and this by a wire 17 is connected with one terminal of a call-generator G, which may be of any desired type, although I prefer a power-driven magneto. The other pole or terminal of the said generator connects by wire 18 with the lever l of

the switch S, and the remaining contact-button of the said switch is connected with the earth by a ground wire. By means, then, of this switch the call-generator can be closed either 5 in an earth-completed or in a metallic circuit.

When the switch-lever is placed on the button v^2 , the circuit-changers k , or either of them, being depressed, the two terminals of the generator are virtually extended to the 10 tip and sleeve of the corresponding plug, and call-signals can be sent over the two wires of a metallic circuit with which the said tip and sleeve may be connected; but if the switch-lever be placed on the button v it will be seen 15 that the springs d' only are connected with the generator, the other pole of said generator being grounded, and that the tip only of a plug connected with the operating-spring d' becomes the generator-terminal. Under such 20 circumstances, that wire of a metallic circuit only which comes in contact with the tip of the plug is connected with the generator, and over it only will the outgoing call be sent. If any earth branch be connected with the said 25 wire and signal-receiving devices be included in said earth branch, it is evident that the said devices will be responsive to a call so sent, although they will be inert when calling-currents are caused to traverse the 30 metallic circuit, and in the same way call-receiving devices included in the circuit of the two line-wires closed at the ends as a metallic circuit will respond when the generator is included in said metallic circuit, but will be 35 responsive to the generator when grounded in the manner described above.

I will now trace out the line-circuits from the central station C to the sub-stations A and B, and as the principle of the invention 40 is the same without regard to the number of circuits it is sufficient to show and describe a single circuit. At each sub-station there is the usual telephone outfit, comprising the transmitting-telephone T, the receiving-telephone t , a call-bell D, a call-generator G' for sending outgoing calls, an automatic switch H, serving as a telephone-support and acting in its normal position to keep the telephones 45 disconnected, the transmitter battery-circuit open, and the bell branch in circuit, and in its converse position to disconnect the calling apparatus to close the local-battery circuit and to connect the telephones. The switch H at sub-station B has an additional function 50 to which I will hereinafter advert. The wires 55 8 and 9 at stations A and B are the conductors of the transmitter local circuit. Leading from one pole of the battery N the wire 8 passes to the movable portion y of a circuit-closer for this circuit operated by the automatic switch-bar h from the other or fixed contact x of said circuit-closer. The other 60 wire 9 of the local circuit passes to the electrodes and primary helix of the induction-coil in the transmitter in a manner well understood, and the circuit then returns by the 65 wire 10 to the other pole of the battery N.

These connections are identical at both stations.

The main line of the metallic circuit L 70 when at rest is from the jack-spring s , with which the plug-tip when inserted makes contact by main wire 1 straight to the most distant station B. There it is permanently attached to the switch-bar h . The line being 75 at rest the switch-bar h makes contact with the stop i and the circuit continues thereby and by wire 21 to the call-generator G', wire 22, call-bell D, and then by main-line wire 2 to the intermediate sub-station A. Here there 80 is a manual circuit-changer J, forming, practically, a double key, and consisting of two conducting springs or stems j and m mechanically united, but electrically separated by the insulating-blocks z and z' , and both 85 governed by the same press-button u . When at rest, this key has its stem j in contact with a conducting-block, forming a back contact therefor, but capable of being disconnected therefrom, and serving also as a front contact for the other stem m when the press-button is pushed. The line 2 from station B is 90 united to the stem j of this key, and thus continues by way of the conducting-block out, passing therefrom to the central station C, 95 where it reaches the spring-jack from which it started, connecting with the frame f thereof. One of the wires of the said circuit thus connects with the jack-spring s and the other with the jack-frame f . The call-communicator a of this line is looped by the wires 19 and 20 between the insulated contact-screw q of the spring-jack on which the spring s normally rests and the jack-frame f , and when 105 the plug p is withdrawn from the jack is in the circuit.

The above description shows that the call-bell of station B is included in the direct metallic circuit L, and hence that calls sent from the central station C over said circuit (the switch S being placed on the button v^2) 110 will operate the said bell and give the call-signal to station B. It also shows that the call-bell magnet of sub-station A is not in the said metallic circuit.

Referring to that portion of the diagram which represents sub-station A it will be found that the condition of the circuit there is, as usual, controlled by the automatic switch H. From any convenient point n on the main line 1 a branch wire 3 leads to the bar h of switch H at station A. In the diagram the switch is in its upper position, the receiving-telephone having been removed from its support; but in its resting position, the telephone being assumed to be in place, the bar h will 120 make contact with the stop i' , and the calling branch circuit would continue therefrom by wire 5 through bell D, wire 6, generator G', wire 7 to the double key J. It here is united 125 to the stem m thereof, which normally presses against its back contact-stop o , and then goes on by wire 23 to the next sub-station B, where 130 it passes by way of a circuit-breaker, shown

as a spring-tongue y' attached to the under side of the bar of the automatic switch H , and normally making contact with a stop i' , to which the wire 23 is united, a wire 24, a 5 manually-operated key or press-button k^3 , its back contact o' and wire 25 to earth at Q^2 . The call-bell of sub-station A is thus shown to be in a branch circuit, leaving the main-line wire 1 at n and running to earth at station B. It is necessary that it should be extended to B, in order that B, when using the line for conversation, shall not be exposed to interruption by A working his call-generator, and the two circuit-breakers included in the 10 15 said branch line at B enable B to fully protect himself. The upper one y' is automatically operated and acts to break the branch circuit whenever B removes his telephone from the switch-bar h , and the lower one k^3 is to be manually operated by B when sending outgoing calls, for a purpose to be hereinafter explained. Therefore, since the call-bell of A is in the above-described earth branch, it is evident that whenever the 20 25 central station desired to signal A the switch S of the generator will be turned to v , thus grounding one pole of the said generator, and the currents then sent to line will pass over the circuit from the ground at C to the ground 30 35 at B through the call-bell at A, and will operate the said bell; but the bell at B will not be in this circuit and will not ring.

It is evident that the earth signaling branch might be interchanged from the side 1 to the 40 45 side 2 of the metallic circuit, provided the earth-switch were also changed to the other side of the generator; but I prefer the arrangement I have described, because it tends to uniformity, for if it be clearly understood that the generator-switch is at all times to be placed on such side of the generator as will tend to make the tip of the plug the line-terminal of said generator, and that the earth branch passing through the bell of station A 50 55 is always to diverge from line-wire 1, leading to the jack-spring, there will be no opportunity for confusion, especially as in the single-line circuits the line always passes from the spring of the jack and not from the frame.

Both of the sub-stations A and B have clear metallic talking-circuits without any interposed electro-magnets to mar or subdue the 60 65 quality of the transmitted speech. If A be using the circuit telephonically, his circuit, as shown, is from the point n on line-wire 1 to the switch-bar h , its upper contact-piece j' , wire 26, transmitter T , wire 27, receiver t , and wire 28 to the point 4 on the main line 2, the remainder of the circuit working inward be- 70 75 80 85 90 95 100 105 110 115 120 125 130 135 140 145 150 155 160 165 170 175 180 185 190 195 200 205 to talk together, the connections of both are also as described. It is true that when the nearer station is connected for conversation through the central station the distant-station bell is connected in parallel circuit therewith, and also that when the two sub-stations are talking together the central-office annunciator is in parallel circuit with them. When A wishes to send a call to the central station, the press-button u of the circuit-changer J is pressed, and by this action the normal earth signal branch is broken between m and o , the call-instruments at A are transferred from the said earth branch to the metallic main-line circuit, and the metallic circuit beyond A leading to B is opened at the points j and n' , and B cannot, therefore, interrupt the operations of A. When B wishes to signal the central station, no other action is absolutely necessary than to operate the generator G' , the instruments being already included in the metallic main circuit; but as a matter of precaution, both to prevent an immediately following or simultaneous ring by station A and also to prevent the unintended ringing of the bell at A when B sends the call, which would happen if a ground or escape were on any part of the wire 2 between M and M' , I supply the manual circuit-breaker k^3 in the earth branch at B, and I prefer that the operator there while sending a call should press the button of said circuit-breaker, and thus open the circuit of the earth branch.

I claim as my invention—

1. A metallic circuit extending between a central and two sub stations, the electro-magnetic call-bell at the most distant sub-station being included directly in said circuit and that of the intermediate sub-station in a branch circuit diverging from one of the wires thereof at said intermediate station and extending to an earth terminal at the outermost station, a call-sending generator at the central station, and a switch therefor determining by its position the connection of said generator in said metallic circuit for the purpose of individually ringing the bell of the most distant sub-station, or in an earth-completed circuit including the branch leading through the call-bell of the intermediate station, for the purpose of operating said call-bell.

2. The combination, substantially as hereinbefore described, of a metallic telephone-circuit extending from a central station to two sub-stations, an earth branch extending 5 from one of the wires of said metallic circuit at the intermediate station to earth at the outermost station, call apparatus at the outermost sub-station, included in the said metallic circuit, call apparatus at the intermediate 10 sub-station, included in said earth branch, a call-generator at the said central station, adapted for connection in the said metallic circuit, together with the call apparatus at the outermost sub-station, and to actuate the 15 same, and switching devices also at the said central station, whereby one terminal of the said generator may be disconnected from the said metallic circuit and transferred to an earth connection, whereby an earth return- 20 circuit is completed through the call apparatus at the intermediate sub-station for the purpose of operating the same and selectively signaling the said station.

3. The combination, substantially as hereinbefore set forth, in a telephone system, of a metallic telephone-circuit uniting a central station with two sub-stations, to call sending and receiving appliances of the most distant station being normally included directly in 25 the said metallic circuit and those of the nearer or intermediate station being included in an earth branch thereof, as described, a single annunciator included in the metallic circuit at the central station, and a circuit- 30 changing device located at said intermediate sub-station, in its normal position maintaining the continuity of both metallic circuit and earth branch, but capable of being moved into a second position, the call appliances be- 35 40 45 50 55 60 65 70 75 80 85 90 95 100 105 110 115 120 125 130 cuit extending from a central station to two sub stations, a spring-jack at the central station, comprising a metallic socket or frame connected with one of the main wires of said circuit, an insulated contact set in said frame, and a contact-spring forming the terminal of the other main wire, insulated from said frame and bearing on said contact-point, an annunciator in a loop from said insulated point to 5 said frame, a branch at each sub-station from the line-wire leading from said contact-spring, said branch extending to the automatic telephone-supporting switches of said stations, a normally-closed extension of the said branch 10 at the outermost sub-station leading through call apparatus to the main wire representing the spring-jack frame, a normally-closed extension at the intermediate sub-station leading from said branch there through the signaling-instruments of such station to earth at 15 the most distant station, a branch at each sub-station from that wire of the metallic circuit leading from the spring-jack frame, the said branches being normally open and including 20 at each sub-station the telephones thereof, a 25

generator at the central station, a switch therefor to connect the same with both wires of the metallic circuit or with that one connected with the contact-spring of the spring-jack at will, a circuit-changer at the intermediate sub-station adapted to transfer the signaling apparatus there from the earth branch to the main circuit for sending outgoing signals, an automatic switch at the intermediate sub-station to disconnect the earth branch and simultaneously to close the telephone branch as a bridge between the two main wires, and a similar switch at the terminal station acting to disconnect the call apparatus and to substitute the telephones therefor, substantially as described. 30 35 40

In testimony whereof I have signed my name to this specification, in the presence of two subscribing witnesses, this 20th day of June, 1890.

JAMES L. MCQUARRIE.
